(57) **CLAIM**

The ornamental design for a fence topper as shown and described.

DESCRIPTION

FIG. 1 is a perspective view of a fence topper showing my new design.

FIG. 2 is a front end view of the fence topper, the rear end view being a mirror image of the front end.

FIG. 3 is a right side elevational view of the fence topper, the left side elevational view being a mirror image of the right side.

FIG. 4 is a top view of the fence topper.

FIG. 5 is a bottom view of the fence topper; and, FIG. 6 is a perspective view of a length of the fence topper attached to the top of a spiked fence outlined by broken lines. The spiked fence outlined by broken lines in FIG. 6 depicts the nature and environmental use of the fence topper and forms no part of the claimed design.
